Sellors Patent

A patent is granted to the above Seller Patent and the key part of the
Invention is a description to the uses of the said Eliza A. Hubbard
and of the Improvement to Patented Oct. 20, 1832.

It is to be known that I, Eliza A. Hubbard, a citizen of Newbury,
in the County of Rockingham, State of New Hampshire, have invented a new
and useful Improvement, to which the following is a full and exact description
thereof.

A small Island is made of sand and is raised in length to the size
of a building upright to the height of six inches and placed at the end of
the ground-work it is a square having in the top in which the height and
width are equal with notches and figures raised upward and down
one and eighteen inches from this pillar are two pyramids in the ground-work
turning at right angles and intersecting in the center of the pillars
which pillars are two inches above having a concave half Circle
in the top of each to receive two arms extending in opposite points from the end
of the beam other than the one above mentioned and length of beam
one and one half feet intersect the circles in the top of the two pyramids.

These arms suspend the beam bearing at its end the other
end to move upward down. To one side of each end arm is a projection
of the distance of one and one half inches and turning at right angles
from the other point bearing on which the cricket for the scoop rests
and this projection is the intersection of said arm with the beam and
in a opposite direction from that of the beam six inches and then turning
at right angles and brought to a pivot bearing to receive the Cricket
for the scoop. On the other end of the ground-work are the projections
six inches above mentioned only the pillars have open spaces in the
center of the circles a crook bar is laid into these mortises a pivot bar
is inserted and then a suspending link on each.

923 X

Then another Construction of similar proportions, and pivot bearing similar in dimensions to the one above. A central vertical of the beam is also provided on the two suspending arm. The Centre Coupling links them a Cricket with four feet Circular Concave at the lower end of each is set in the bearing at the right angles of the proportions.

The Cricket is circularly shaped at the top to receive the timber of. The weight is obtained by placing the load on the graduated beam. The Counter balance is composed wholly of iron or iron other material. It is also portable. No screw is also portable Separate from the balance.

There are some ancient principles in it such as the tie strap the beam is adjusted with notches and figures. Dr. Whistler do not claim as my invention but what I mean to claim is the general construction of it but more particularly the system of weight with a screw and beam without ends. Besides using it to weigh in various and for family use I design using a platform in the place of the tie strap to and substitute it for platform scales in some cases.
